CLAIM

The ornamental design for an earphone, as shown and described.

DESCRIPTION

FIG. 1 is a perspective view of an earphone;

FIG. 2 is a front view thereof, the rear interior of the ear insert is not part of the claimed design;

FIG. 3 is a rear view thereof;

FIG. 4 is a top plan view thereof;

FIG. 5 is a bottom plan view thereof;

FIG. 6 is a right side view thereof; and,

FIG. 7 is a left side view thereof.

The broken lines showing on the drawing disclosure are for illustrative purposes only and form no part of the claimed design.
